(57) **CLAIM**

The ornamental design for a quantum computer, as shown and described.

DESCRIPTION

FIG. 1 is a perspective view of the quantum computer in accordance with our new design.

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The broken lines in the figures depict portions of the quantum computer that form no part of the claimed design. All unshaded surfaces form no part of the claimed design. The appearance and configuration of the solid line features visible in FIGS. 5 and 7 are the same as the corresponding features visible in FIG. 1.

1 Claim, 7 Drawing Sheets
